UNITED STATES PATENT OFFICE

98,185

DESIGN FOR A BINOCULAR TELESCOPE

Milton Reynolds, Chicago, Ill.

Application September 27, 1935, Serial No. 58,739

Term of patent 14 years

To all whom it may concern:

Be it known that I, Milton Reynolds, a citizen of the United States, residing at Chicago, in the county of Cook and State of Illinois, have invented a new, original, and ornamental Design for a Binocular Telescope, of which the following is a specification, reference being had to the accompanying drawing, forming a part thereof.

The figure is a perspective view of a binocular telescope embodying my new design, the appearance of the telescope being the same on opposite sides.

I claim:

The ornamental design for a binocular telescope substantially as shown and described.

MILTON REYNOLDS.

Certificate of Correction

Design No. 98,185.

January 14, 1936.

MILTON REYNOLDS

It is hereby certified that error appears in the above numbered design requiring correction as follows: In the heading to the printed specification, line 5, Term of Patent, for "14 years" read $3\frac{1}{2}$ years; and that the said Letters Patent should be read with this correction therein that the same may conform to the record of the case in the Patent Office.

Signed and sealed this 22nd day of December, A. D. 1936.

[SEAL]

HENRY VAN ARSDALE,
Acting Commissioner of Patents.
